CLAIM

The ornamental design for an electric toothbrush handle, as shown and described.

DESCRIPTION

FIG. 1 is a front perspective view of an electric toothbrush handle according to an embodiment of the new design; FIG. 2 is a rear perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; and, FIG. 8 is a bottom plan view thereof.

The broken lines in the drawings illustrate portions of the article that form no part of the claimed design.
